DAVID C. LAMB, OF NAPPANEE, INDIANA, ASSIGNOR TO LAMB BROS. & GREENE, OF NAPPANEE, INDIANA, A CORPORATION OF INDIANA.

ELECTRIC-CONDUCTOR TAKE-UP.

1,106,321.

Specification of Letters Patent. Patented Aug. 11, 1914.

application filed December 4, 1913. Serial No. 204,742.

To all whom it may concern:

Be it known that I, DAVID C. LAMB, a citizen of the United States, and a resident of Nappanee, Elkhart county, in the State of Indiana, have invented a new and useful Improvement in Electric-Conductor Take-Ups, of which the following is a specification.

This invention relates to reels and containers for the flexible connecting cords or conductors of electric lights and fans, vacuum cleaners, telephones, and other portable electric apparatus.

It relates especially to the electro-mechanical construction of the reels or "take-ups" of such devices; and the improved take-up is adapted for both ceiling or wall containers, and those which form part of the portable apparatus, as the hollow base of a table lamp.

The leading object is to take care of a long connecting cord when the lamp or other electric article is not in use. The "cord" thus cared for, in case of ceiling or wall containers, consists of the incased pair of separately insulated wires leading to and from the lamp socket or its equivalent; in the case of a container forming part of the portable apparatus, it consists of prolongations of the pair of insulated wires within the electric conduit, leading to and from the reel, or take-up.

The distinguishing objects of the present invention are to facilitate attaching and detaching both cords at the reel or take-up, so as to meet the requirements of dealers; to render the device secure against danger from sparking, so as to meet the requirements of fire underwriters; and to render the construction at once simple and effective by making all the principal parts of insulating material, especially vulcanized fiber.

The improved take-up is thus adapted to have cords of a different color or of greater conductivity or length quickly substituted without danger from imperfect electrical contacts; and a superior article may be made and sold at a low price.

The invention consists in certain novel combinations of parts, hereinafter particularly described and claimed.

A sheet of drawings accompanies this specification as part thereof.

Figure 1 represents a side view of a ceil-

ing attachment embodying the improved take-up, partly in section; Fig. 2 is an elevation projected from Fig. 1, with the shell of the container detached; Fig. 3 represents a section on the line A—B, Fig. 1; Fig. 4 represents a section on the line C—D, Fig. 60 2; Fig. 5 is a perspective view of the bracket shown at the bottom in Fig. 4, detached; Figs. 6 and 7 are perspective views of a detachable spool member exposed by detaching said bracket; Fig. 8 is a view of a detachable wire bail or "pliers" for withdrawing said spool member; and Fig. 9 is an elevation of a portable lamp representing a modification.

Like reference characters refer to like parts in all the figures.

The container, *a* or *a*², of the improved reel or take-up, *b*, or *c* may be of any desired external shape and material. It is usually metallic as represented in Fig. 1 excepting a top or bottom disk and a cord-hole bushing, represented respectively at 1 and 2, both of which, as accessories of the improved take-up, are preferably and conveniently of insulating material. This material and all insulating material hereinafter referred to is 70 75 80 85 90 95 100 105 insulating material represented as a whole by *c*, is located within the container *a* or *a*² and concealed thereby. Said screws 3 and 4 permanently attach the major part of the take-up; and said screw 5 attaches a detachable bracket, 6, shown detached by Fig. 5, and is the only screw which need be removed when it is desired to detach either or both cords 1' and 2', from the exposed take-up. The respective cords 1' and 2' are attached to said bracket 6, and to a detachable spool member, 7, which is shown detached by Figs. 6 and 7. The body of said bracket 6 is of insulating material, as is that of said spool member 7; and the latter is normally located within a chamber formed by the sleeve of the take-up. The sleeve of the take-up is wholly of insulating material. All electric contacts are thus located within said sleeve of insulating material, and any danger from sparking is precluded. The body of an axial spindle, 9, which extends through the space within said sleeve and through said bracket 6 and member 7, is also made of insulating material.

The cord 1' is carried through a hole 10, Fig. 5, in the bracket 6, and bifurcated, a sufficient length of its respective insulated wires having been freed from the customary outer covering common to both, and the bared extremities of the respective wires are screw-clamped in electric contact with the knees of a pair of contact springs, 11, 13, which project from the back of the bracket. Said springs, 11, 13, contact respectively at their extremities with metallic rings, 12, 14, forming crown flanges on the outer face of said member 7, as shown in Fig. 6, and extended through to the back of the same, as shown in Fig. 7, where the bared extremities of the bifurcated inner end of the cord 2' are screw-clamped thereto. Compare Figs. 1 and 4. To facilitate so attaching the cord 1' to the bracket 6, it is only necessary to detach the bracket by removing said screw 5. To facilitate removing the spool member 7 to expose its back, the inner contact ring 14 on its face, which is exposed by detaching the bracket 6, is provided with diametrically opposite holes, 15, Fig. 6, fitted to the jaws of a detachable bail or "pliers", 16, Fig. 8, which is conveniently formed of wire as shown. If a cord is to be detached from the spool, it should first be slackened to facilitate pulling a sufficient length of the cord 2' through the hole, 17, Fig. 1, in the sleeve of the spool 8, through which the cord extends outward.

The spool 8 is normally locked, as is customary, by a self-releasing device, 18, 19, 20, the members of which are shown in Fig. 3. The movable members of this device are pivoted to a plug 8' (of insulating material) within said sleeve of the spool 8, the stationary member, 18, being fast on the adjacent surface of the housing, 21, of the customary winding spring, 22, Fig. 4. The inner spring end is attached to a short metallic spindle, 23, which forms part of the spindle 9, and is coupled to the adjoining end of the spindle body of insulating material within the same, and said spring 22 rotates the spool 8 through the medium of said spindles 23 and 9, when the spool is released; the latter being accomplished by a quick jerk on the cord 2' in customary manner. A metallic knee, 24, which may be integral with said housing 21, interacts with the attaching screws 3 and 4; and a smaller metallic knee, 25, inseparably attached to the body of the bracket, 6, interacts with the attaching screw 5. In said main species represented by Figs. 1 to 8, inclusive, the cord 1' extends to the bracket 6 from the electric conduit through a hole, 26, Fig. 1, in the disk 1 of the container a , and the cord 2' extends from the spool 8 through the bushing 2 to the lamp socket or its equivalent, said bushing being located centrally at the extremity of the container.

In the modification represented by Fig. 9, the container a^2 forms the base or a part of the base of a portable lamp, and the cord hole provided with the bushing 2 is or may be located in the side of the container as shown. When the improved take-up is thus combined with an electric apparatus, the cord 2' is provided with a suitable plug d , Fig. 9, and connects the spool 8 with the conduit wires; while the cord 1' extends from the bracket 6 to the lamp socket, or its equivalent, of the portable apparatus. The reel or take-up b , Fig. 9, including its said spool 8 and bracket 6, is of the construction more particularly described herein with reference to the reel or take-up c , Figs. 1-7.

For the purposes of this invention the winding spring and self-releasing detent may be of any known or improved construction; and other like modifications will suggest themselves to those skilled in the art.

Having thus described said improvement, I claim as my invention, and desire to patent under this specification:

1. An electric conductor take-up having, in combination with two flexible cords each comprising a pair of insulated wires, a rotatable spool of insulating material having an apertured sleeve portion and a chamber within the same, a bracket which closes one end of said chamber and supports that end of the spool, said bracket having a body of insulating material, and electrical connections carried by said spool and said bracket, respectively; said electrical connections comprising contact springs projecting endwise within said chamber to which the bifurcated inner end of one of said cords is electrically connected, and metallic rings concentric with said spool forming crown flanges adapted to contact with the extremities of said springs respectively and electrically connected with the bifurcated inner end of the other of said cords.

2. An electric conductor take-up having, in combination with two detachable flexible cords each comprising a pair of insulated wires, a rotatable spool of insulating material having an apertured sleeve portion and a chamber within the same, a detachable bracket which normally closes one end of said chamber, and supports that end of the spool, said bracket having a body of insulating material and contact springs projecting endwise from its back to which the bifurcated inner end of one of said cords is electrically connected, and a removable spool member normally located within said chamber having a body of insulating material provided with concentric metallic rings forming crown flanges on the outer face of said member, adapted to contact with the extremities of said springs, and extended through to the back of said member, and means for electrically connecting therewith the bifur-

cated inner end of the other of said cords which extends outward through the aperture of said sleeve portion of the spool.

3. The combination, in an electric conductor take-up, of a rotatable spool of insulating material having an apertured sleeve portion and a chamber within the same, a detachable bracket which normally closes one end of said chamber and supports that end of the spool, said bracket having a body of insulating material and contact springs projecting endwise from its back and adapted for the attachment thereto of the respective wires of a connecting cord at said back of the bracket, a removable spool member normally located within said chamber having a body of insulating material provided with concentric metallic rings forming crown flanges on the outer face of said member adapted to contact with the extremities of said springs and extended through to the back of said member, and means for electrically connecting therewith the respective wires of another connecting cord; one of said rings being adapted for the temporary attachment thereto of means for removing and replacing said spool member.

4. The combination, in an electric conductor take-up, of a rotatable spool of insulating material having an apertured sleeve portion and a chamber within the same, a detachable bracket which normally closes one end of said chamber and supports that end of the spool, said bracket having a body of insulating material and contact springs projecting endwise from its back and adapted for the attachment thereto of the respective wires of a connecting cord at said back of the bracket, a removable spool member normally located within said chamber having a body of insulating material provided with concentric metallic rings forming crown flanges on the outer face of said member adapted to contact with the extremities of said springs and extended through to the back of said member, and means for electrically connecting therewith the respective wires of another connecting cord; one of said rings being provided with diametrically opposite holes, whereby it is adapted for the temporary attachment thereto of means for removing and replacing said spool member.

5. In combination with two detachable cords each comprising a pair of insulated wires, a cord reel and container, the former comprising a rotatable spool of insulating material having an apertured sleeve portion

and a chamber within the same, a rotatable spindle having a body of insulating material fast within said spool and extending axially therethrough, a winding spring and automatic controlling means connected mechanically with said spindle, means for supporting said reel within said container, including a detachable bracket having a body of insulating material and contact springs on its back to which the respective wires of one of said cords are electrically connected, and a removable spool member normally located within said chamber having a body of insulating material provided with concentric metallic rings on its outer face adapted to contact with said springs, and extended through to the back of said member, and means for electrically connecting therewith the respective wires of the other of said cords which extends outward through the aperture of said sleeve portion of the spool.

6. In combination with two flexible cords each comprising a pair of insulated wires, a cord reel and container the former comprising a rotatable spool of insulating material having an apertured sleeve portion and a chamber within the same, a bracket which closes one end of said chamber and supports that end of the spool, said bracket having an apertured body of insulating material and contact springs on its back to which the respective wires of one of said cords extending through said bracket are electrically connected, and a spool member within said chamber having a body of insulating material provided with concentric metallic rings on its outer face adapted to contact with said springs, and extended through to the back of said member, and means for electrically connecting therewith the respective wires of the other of said cords, which extends outward through the aperture of said sleeve portion of the spool; said container having an apertured disk of insulating material through which the first named of said cords extends from an external conduit and by which said reel is supported, and a metallic shell having a cord hole provided with a bushing of insulating material through which the second cord extends from the spool to a lamp socket or the like, substantially as hereinbefore specified.
